Primary Examiner — Robert Delehanty(74) *Attorney, Agent, or Firm* — Eliezer IP(57) **CLAIM**

The ornamental design for a portable bidet, as shown.

DESCRIPTION

FIG. 1 is a perspective view of a portable bidet showing my new design;

FIG. 2 is a rear view thereof;

FIG. 3 is a front view thereof;

FIG. 4 is a right side view thereof;

FIG. 5 is a left side view thereof;

FIG. 6 is a top view thereof; and,

FIG. 7 is a bottom view thereof.

The broken lines shown in the drawing views are included for the purpose of illustrating a portion of the portable bidet that form no part of the claimed design.
